UNITED STATES PATENT OFFICE.

WRIGHT J. SEATON, OF WYANDOTTE, KANSAS.

AUTOMATIC SAFETY-BRAKE FOR ELEVATORS.

SPECIFICATION forming part of Letters Patent No. 279,024, dated June 5, 1883.

Application filed April 3, 1883. (No modcl.)

To all whom it may concern:

Be it known that I, WRIGHT J. SEATON, of Wyandotte, in the county of Wyandotte and State of Kansas, have invented a new and Improved Automatic Safety-Brake for Elevators, of which the following is a full, clear, and exact description.

My invention consists of a brake for elevators, contrived for automatically operating in case the rope breaks or other accident causes the carriage to fall, also having provision to be set in action by a person on the carriage in case it should fail to act for any cause, and also arranged to be used as a brake for regulating the descent of the carriage independently of the machinery for operating the carriage, all as hereinafter fully described.

Reference is to be had to the accompanying drawings, forming part of this specification, in which similar letters of reference indicate corresponding parts in all the figures.

Figure 1 is a front elevation of the elevator-carriage and the brake apparatus, also of a portion of the ways in which the carriage runs. Fig. 2 is a vertical section of Fig. 1 on the line x x. Fig. 3 is a horizontal section on the line y y of Fig. 1, and Fig. 4 is a detail of the gripping device of the brake.

Under the floor a of the carriage, and in a box, b, suitably attached to each side and in suitable relation to the dovetail guide-ribs c of the vertical ways d, I arrange the blocks or shoes e to bear against the front edges of the ribs c, and the gripping-jaws f to grip the sides of the ribs, and constituting the means of binding the carriage to the ribs for stopping it. The shoes e, besides being suitably confined in the box b, are fitted on the right and left handed screw-threaded shaft g, so that when it turns one way they are forced against the ribs to produce the friction for stopping the carriage, and when it turns the other way they relax the pressure and slide along the ribs without resistance. The shoes e also have wedging sides i, which actuate jaws f at the same time that they are thrust against the faces of the ribs, and cause said jaws to grip the sides of the ribs; also, for a means of resisting the descent of the carriage.

It will be seen that by the dovetail form of the rib and its relative arrangement with the

shoes and jaws—that is to say, so that the jaws draw it toward the shoes—the side pressure of the shoes is counteracted by the jaws, so that the spreading of the ways by the shoes is prevented and the contraction of the carriage by the jaws is counteracted, thus avoiding any undue strain either way on the ribs c.

To set the brake in action in case the carriage-rope j breaks, a rope, k, is stretched from end to end of the range of the carriage and made fast at its ends to timbers l m, passing over a grooved pulley, n, on shaft g, and a tightening-pulley, o, in a movable support, p, and having a weighted lever, q, connected to it, which is held out of action in the position represented by the dotted lines in Fig. 2 by the lever s, which has a latch, t, connecting it with the trip-stud catch u on one of the uprights v of the carriage, by which it is tripped when the rope breaks by the spring w, lever x, and rod y, the said stud-catch u being attached to the end of rod y, so as to be raised by it when the spring w, being released from the weight of the carriage, throws down the lever x and raises up the rod y.

To enable the person on the carriage to trip lever s in case it should fail for any cause to be tripped automatically, and also to thrust down the weighted lever q, the latch t is pivoted to lever s, and a small trip-lever, z, and a handle, a', are applied to said lever, so that by grasping the handle and lever z he may disconnect the lever s and swing it down so as to throw the tightener o on or toward pulley n and set it and the screw-shaft g in motion. A spring, b', is also fitted to the lever s to insure its operation. The latch t has a spring, c', to hold it in engagement with the catch-stud u.

The weighted lever q is fitted on a shaft, d', that is supported in suitable bearings under the floor of the carriage in which to turn properly, and is connected to the tightener by the crotched connecting-rod e' and crank f', and to the lever s it is connected by crank g' and connecting-rod h'.

In order that the lever s, latch t, and catch u shall not be subject to much stress of the weighted lever when set, and thus lessen the friction of the parts, so that the action will be more certain, the lever q is so curved and the weight j' is suspended on it by a roller, k',

whereby it runs down near the fulcrum of the lever to rest until after the trip has been detached. Another purpose is also accomplished by this movable arrangement of the weight—
5 viz., more gradual action of the brake-shoes and gripping-jaws on the guide-ribs *c*, thus preventing shocks and jars and undue strain in the stopping of the carriage.

It will be seen that by the proper manipulation of the lever *s* to regulate the pressure of the tightening-pulley *o* the attendant may set the brakes to govern the descent of the carriage independently of the operating machinery; and in case the brakes should be screwed 15 up too tight they can be released by a pinion-wheel, *l'*, gearing with a toothed rim, *m'*, on the pulley *n*, and having a shank, *n'*, to which a socket wrench or crank may be applied.

For the purposes of a hand-brake to regulate the descent of the carriage, the weighted lever *q* may be dispensed with, the pressure 20 of the hand-lever *s a'* alone being employed; but it is better with the weighted lever, because it lessens the labor of the attendant. The 25 spring *o'* at the end of the lever *q* is employed to cushion the stop of the weight *j'* at the end of the lever.

To insure fair bearing of the faces of the jaws *f* on the sides of the ribs *c*, I have made 30 the face-sections *f²* separate and connected them to the main portions of the jaws by joints *f³*, forming substantial connection of said face-sections, and allowing them to vibrate suitably for accommodating them to any variations in 35 the angles of the sides of the ribs and to compensate for wear.

Having thus described my invention, what I claim as new, and desire to secure by Letters Patent, is—

40 1. The combination of the shoes *e*, gripping-jaws *f*, right and left screw-threaded shaft *g*, and means to operate said shaft, with the guide-ribs *c* and an elevator-carriage working along said ribs, substantially as described.

45 2. In a brake device for an elevator-carriage, consisting of right and left screw-shaft *g*, shoes *e*, gripping-jaws *f*, and the guide-ribs *c*, the said guide-ribs and gripping-jaws beveled, so

that the stress of the gripping-jaws counteracts the pressure of the shoes, substantially as 50 described.

3. The brake-shoes *e*, in combination with right and left screw-shaft *g*, gripping-jaws *f*, and the guide-ribs *c*, and having wedge-shaped sides *i*, to actuate the jaws, substantially as 55 described.

4. In an elevator brake apparatus, the brake-shoes *e* and gripping-jaws *f*, arranged in boxes *b*, attached to the under side of the platform, in combination with the operating-shaft *g* and 60 means for operating it, and with the guide-ribs *c*, substantially as described.

5. The combination of the rope *k*, pulley *n*, tightener *o*, and means for operating the tightener, with the right and left screw-threaded 65 shaft *g* and brake-shoes *e* of an elevator-carriage, substantially as described.

6. The combination of adjusting face-sections *f²* with jaws *f*, ribs *c*, wedge-shoes *e*, and the elevator-carriage, substantially as described. 70

7. The weighted lever *q*, trip-lever *s*, latch *t*, trip-catch *u*, rod *y*, lever *x*, and spring *w*, in combination with the tightener *o*, rope *k*, pulley *n*, and the right and left screw-threaded 75 shaft *g*, which operates the brake-shoes, substantially as described.

8. The handle *a'* and trip-lever *z*, in combination with the latch *t*, levers *s*, catch-stud *u*, weighted lever *q*, and the tightener and rope for actuating the brake apparatus, substantially as described.

9. The combination, in an automatic tripping apparatus for elevator-carriages, of a weighted belt-tightening lever, whereon the weight shifts along the lever to or near the 85 fulcrum to relieve the tripping apparatus when set, and runs out along the lever to apply the power when tripped, substantially as described.

10. The combination of pinion *l'* with the pulley *n*, shaft *g*, and the brake-shoes and carriage, substantially as described. 90
